UNITED STATES PATENT OFFICE.

EUGENE E. EDENHARDER AND JACOB E. EDENHARDER, OF WEST ALLIS, WISCONSIN,
ASSIGNORS OF ONE-THIRD TO HELEN EDENHARDER, OF WEST ALLIS, WISCONSIN.

DEVICE FOR DELIVERING MAIL BAGS FROM RAILWAY CARS.

Application filed January 20, 1926. Serial No. 82,560

The invention relates to devices designed for effecting the safe delivery of mail bags from moving railway trains, and resides in a construction one part of which is attached 5 to the railway car and is carried therewith and the other part of which is fixed at the railway station or other place at which the bag of mail is to be delivered from the car at the time that the latter passes the said 10 station or place.

The part of the device which is carried by the car is supported at the inside of the car, in which position it may receive the mail bag to be delivered, and then be swung into 15 a position exterior to the car so as to be brought into position for delivery of the mail bag, when the moving part and stationary part are brought into co-operative relation.

20 The movable part is provided with means for retaining the mail bag until engagement of the latter with the fixed part. Upon such engagement, the mail bag retaining devices upon the movable part are operated automatically to effect the release of the said 25 retaining means, and so free the mail bag for deflection from the line of its movement into the compartment with which the fixed part is provided, such deflection being caused by 30 certain elements positioned upon the fixed part.

The compartment in the fixed part is provided with a shield or cover which will serve to exclude in a very material degree rain and 35 snow, which cover is automatically operated so as to admit the mail bag into the receiving compartment and is automatically restored to its normal position thereafter.

The novel features residing in the invention will now be particularly described, and then set forth in the appended claims.

In the drawing:

Figure 1 is a side view of a railway mail car showing the mail bag supporting means as in position for effecting delivery, and showing also the fixed part of the transferring device as in position for receiving the mail bag when discharged from the moving car.

Fig. 2 is a view, somewhat enlarged, illustrating the action of delivery of the mail bag from the car into the fixed compartment.

Fig. 3 is a view from the left of the devices shown in Fig. 2.

Fig. 4 is a plan view of the devices shown

in Figs. 2 and 3, the side of the car being 55 shown in horizontal section.

Fig. 5 is a plan view of the fixed compartment, the latter being shown as open at the top.

Fig. 6 is a vertical sectional view through 60 the fixed compartment, showing the arrangement of the cover or shield for closing the same, the automatic operation of the latter being illustrated.

In the drawing, the numeral 10 designates 65 a railway mail car, assumed to be travelling in the direction indicated by the arrow in Fig. 1. A bracket 11 is attached at a suitable distance from the floor of the car to the inside of the door frame. The end of 70 the stem of a T-arm 12 is pivoted at 13 to the said bracket. To the head 14 of the T-arm are connected horizontal guides 15 and 16, which for the purposes of the invention, may be spaced bars or a single piece, 75 the extreme edges of which form guideways for the receptacle 17, in which the mail bag to be delivered is placed. The receptacle 17 is a skeleton affair, open at the top and sufficiently closed at the bottom by a grid formation, which latter will retain the bag until 80 delivery is effected. The said grid formation is comprised of two parts, one part 18 being formed as a plurality of fixed members attached to the lower front edge of the receptacle 17, the other part 19 being formed as a plurality of movable members, the latter being pivoted at the rear lower edge of the receptacle. The grid members converge at 85 their lower free ends, and are adapted to support a mail bag in the V-trough or hopper thus created. The rear grid member 19 is provided with an angular arm 20, upon which is positioned counter-weight 21, the purpose of 90 which is to maintain the movable grid in 95 the position shown in Figs. 1 and 2. A depending latch 22 is pivoted at its upper end to the side of the receptacle 17, next to the car, and is provided with a catch 23, the latter being adapted to engage under a projection 24 on that finger of the grid 19 which is nearest to the side of the car, and by this means support the mail bag in the V-trough or hopper until the latch 22 is withdrawn in the manner which will be described later.

As hereinbefore indicated, the receptacle 17 is adapted to move along the guides 15 and 16, and to facilitate such movement, we pro-

vide circumferentially grooved rollers 25, 26, at the top and bottom of the receptacle, the said rollers riding upon the remoter edges of the guides 15 and 16. In order to limit 5 the extent of the rearward movement of the receptacle 17 along its guides, we provide stops 27 for engaging the rear side of the receptacle. Such stops may be formed by turning out the ends of the said guides, in the 10 manner indicated in Fig. 4. Distance pieces 28 may be provided at the end of the guides 15 and 16, so as to contact with the side of the car and maintain the said guides in parallelism with the path of movement of the car. 15 The numeral 30 indicates a compartment fixed at the station or other place where the mail bag is to be delivered, the said compartment being provided with an automatically operating cover for its open top. It may be 20 provided with a hinged door 31 through which the mail bag may be taken from the compartment after delivery has been made. At the front upper edge of the compartment 25 a grid 32 is fixed, the fingers of the grid 32 being so positioned that they will be cleared by the fingers of the grids 18 and 19 in the operation of the device. As so arranged, the grid 32 is adapted to intercept the movement of the mail bag resting in the trough of the 30 receptacle 17, such arresting movement pressing the mail bag against the pivoted grid 19, turning the latter upon its pivot so as to separate the converging members, and deflect the mail bag immediately into the compartment 35 30. In order to permit the discharge of the mail bag, we provide upon the side of the compartment 30 a cam 33 upon the surface of which the lower end of the latch 22 is adapted to ride, and withdraw the catch 23 from its 40 engagement with and support of the pivoted grid 19, permitting the movement of the latter, and the ejection of the mail bag. In order to neutralize the impact of the mail bag against the grid 32 and deflect the mail bag 45 downwardly into the compartment 30, the grid 32 is fixed in the angular position shown in Figs. 1 and 2.

In Fig. 6, we have shown the automatically operating cover or shield effecting a normal closure of the compartment 30. Plates 35 and 50 36, which may overlap slightly at the free edges are pivoted at 37 and 38 to the upper sides of the compartment, and normally held in closing position by means of counter- 55 weights 39 and 40. The plates 35 and 36 are depressed into the dotted line position shown by the movement of the mail bag, which now has no support. When the bag has cleared the cover plates, the weights 39 and 40 restore 60 the cover to its normal position of closure.

In the operation of the device, the receptacle 17 and its supporting structure will be 65 swung to the inside of the car while the latter is moving between mail delivery points. When a station or place at which mail is to

be delivered is approached, the latch 22 will be engaged with the pivoted grid 19, the latter having meanwhile been restored to its normal position through the action of the weight 21. The mail bag 13 is then placed in the receptacle 17, resting in the V-trough or hopper formed by the grids 18 and 19. The delivering apparatus is then swung to the outside of the car, and delivery of the mail bag will take place in the manner hereinbefore described. 75

Having thus described our invention, what we claim and desire to secure by Letters Patent of the United States, is:

1. In a device for delivering mail bags from moving railway cars, a receptacle carried by the car, and having a V-trough or hopper formed of converging grids one of which is movable, and adapted to support a mail bag in position for delivery, in combination with a stationary grid adapted to engage the mail bag and deflect it from the hopper through its movable grid. 80

2. In a device for delivering mail bags from moving railway cars, a receptacle thereon provided with a bottom formed as a V-trough for supporting the mail bag in position for delivery, one side of the trough being movable to release the mail bag, in combination with a fixed compartment for receiving the mail bag, and means thereon for deflecting the mail bag from the V-trough 95 into the said compartment. 90

3. In a device for delivering mail bags from moving railway cars, a receptacle supported within the car and adapted to be thrown to the outside thereof, the said receptacle having a bottom formed as inclined grids, one of which is fixed to the receptacle and the other pivoted thereon, in combination with a fixed compartment and a fixed grid thereon, the latter being adapted to engage the mail bag and move the movable grid to permit deflection of the mail bag into the said compartment. 100

4. In a device for delivering mail bags from moving railway cars, a support pivoted on the car, a receptacle mounted on the said support so as to be moved with the latter into and out of the car, the said receptacle being provided with a movable bottom for supporting the mail bag, and means on the receptacle for retaining the movable bottom in supporting position, in combination with a fixed compartment for receiving the mail bag when delivered, means thereon for effecting such delivery, and means on the fixed compartment for withdrawing the said retaining means to permit such delivery. 110

5. In a device for delivering mail bags from moving railway cars, a receptacle on 125 the car for supporting a mail bag, the said receptacle having a movable bottom formed as a grid member, and means for holding the movable grid member in supporting position, in combination with a fixed receiving com- 130

partment with a fixed grid thereon for deflecting the mail bag, means for releasing the movable grid, and a cover for the compartment operated by the movement of the mail bag into the compartment.

6. In a device for delivering mail bags from moving railway cars, a receptacle on the car for supporting a mail bag and provided with a movable bottom, in combination
10 with a fixed compartment for receiving the mail bag, means on the compartment for de-

flecting the mail bag from the receptacle into the compartment, a hinged cover for the latter which is operated in the deflection of the mail bag, and means for restoring the 15 said cover to normal closing position after delivery of the mail bag has been effected.

In testimony whereof, we have signed our names at Milwaukee, this 11th day of January, 1926.

EUGENE E. EDENHARDER.
JACOB E. EDENHARDER.
